PRINT ROLL AND LIKE ARTICLE

Richard A. Wilkins, Beverly, Mass., assignor to
Industrial Development Corporation, Boston,
Mass., a corporation of Maine

Application August 30, 1930, Serial No. 478,904

2 Claims. (Cl. 101—375)

My invention relates to articles coated by electro-deposition, and particularly, but not exclusively, cylindrical articles such as print rolls and cylindrical cathodes, the latter such as employed 5 in apparatus of the type disclosed by United States patent to Merritt No. 1,601,690, issued September 28, 1926, and also relates to methods of making such articles.

The invention will be best understood from the 10 following description when read in the light of the accompanying drawing of an article made according to the invention, the scope of which latter will be more particularly pointed out in the appended claims.

Print rolls, which commonly are from six inches to six feet in diameter and from one to ten feet long, have heretofore been made of thick walled copper castings, which latter, due to the expensiveness of the material employed and the technical difficulties encountered in forming large castings of that material, are exceedingly costly. According to the present invention, the body of the roll may be formed of an inexpensive, easily cast and easily worked metal, such as cast iron or aluminum, 25 which body is covered with an electro-deposited layer of copper, the latter possessing such properties of hardness, toughness, and uniformity of structure that a greater uniformity in wear is secured as compared to cast copper rolls, while at 30 the same time securing an improved surface for forming the pattern. The improved print rolls are less expensive to produce as compared to cast copper rolls, and have the advantage that when worn, or when refinished by turning operations 35 to remove the patterns, can be readily restored to their original diameters by subjecting them to electro-depositing operations for replacing the copper worn off or removed in refinishng them, whereas cast copper rolls ordinarily must be discarded after they are several times subjected to 40 turning operations for refinishng them, or for truing them to accurate cylindrical shapes to compensate for irregularities in wear. In this latter respect the turnings removed from print rolls 45 constructed according to the present invention may be replaced by electro-deposition, by practice of the method disclosed in the above mentioned patent, thus avoiding the extreme reductions in diameters of the rolls as occur when refinishng 50 cast copper rolls by turning operations.

It will thus be observed, that with print rolls constructed according to the present invention, large economic savings are effected in respect to capital costs and maintenance.

55 The drawing is a perspective view, with parts

broken away, of a print roll made according to the invention.

Referring to the drawing, the print roll illustrated comprises a sleeve 1 conveniently formed of cast iron on which is electro-deposited a layer 3 of suitable metal, as for example copper. At opposite ends of the sleeve are heads 5 having portions providing cylindrical surfaces 7 which fit the inner wall 9 of the sleeve, these heads also having flanges 11 the inner lateral surfaces 12 of which 60 abut with the annular end surfaces of the sleeve, while the peripheral surfaces 13 of the flanges conform to the outer surface 15 of the sleeve. Herein a shaft 17 extends through openings 19 in the two heads 5 for rotatably supporting the roll. 70

It will be understood that, due to the large diameter of the print rolls and due to the difference in coefficients of expansion between the sleeve 1 and layer 3, there is a material tendency of said layer to loosen or partially loosen from the sleeve, 75 the latter causing warping of the surface of said layer from that of the true cylinder. According to the present invention, to overcome these defects, the sleeve 1 is provided with a plurality of inserts 21, which latter conveniently may be in 80 the form of copper or other metallic plugs inserted in the surface of the sleeve prior to electro-depositing the layer 3 thereon. These plugs may be secured in recesses 23 formed in the surface portion of the sleeve in any convenient manner, 85 as for example, by causing them to have a driving fit with the recesses or by screw threading them thereinto, or by "sweating" them to the walls of the recesses after they are inserted. The copper, or like layer, when electro-deposited on the cast 90 iron sleeve 1, will be united electrolytically with the outer surfaces of the plugs 21, and therefore will be substantially integrally united with the same.

The heads 5 are secured to the sleeve 1 in any 95 suitable manner, after which the outer surface of said sleeve, the peripheral portions 13 of the flanges 11 of the heads, and the outer ends of the inserts may be machined to form a fairly accurate cylindrical surface, which latter, prior to 100 electrodepositing the copper layer, may be sand blasted to clean it and to secure better adherence of the copper layer. Prior to electro-depositing the layer 3, the outer surface of the cylinder conveniently may be given a "flash coating" of copper, or like metal, in any convenient manner, as for example, by a sponge plating process or by 105 electro-depositing the flash layer from a copper cyanide solution.

The layer 3, which may be in the order of one- 110

half inch thick, may be deposited by use of the apparatus disclosed in my co-pending application Serial No. 461,091, filed June 14, 1930, in which apparatus the electrolyte is caused to pass rapidly in a swiftly flowing stream through a lead lined trough constituting an insoluble anode, while the roll is partially immersed in said stream of electrolyte and is rotated with its surface in proximity to the walls of the trough, the sleeve 1 being connected to the negative terminal of a depositing source of electromotive force by collector rings temporarily secured to the shaft 17 in electrical contact therewith.

It will be noted, that while the layer 3 is being plated, the current is conducted by the heads 5 from said layer to the shaft 17, which heads, to facilitate this conduction, are preferably made of a low resistance bronze. It will be observed, that by having the peripheral portion 13 of the heads 5 in contact with the layer 3, a low resistance path for the current is provided. Preferably, to permit ready use of a high plating current, say in the order of 6000 amperes for a roll two feet in diameter and five feet long, the abutting portions of the heads 5 and sleeve 1 are sweated together, while the flanges 11 of the heads 5 are of substantial width. Also, by making the flanges 11 constitute the end portions of the cylinder on which the coating 3 is deposited, the thickness of the layer 3 will be maintained at the end of the roll

due to the low resistance of the bronze heads 5, which result would not be so readily secured if the sleeve 1 extended to the extreme end of the roll.

It will be understood that wide deviations may be made from the form of roll disclosed and the materials and steps of the method described without departing from the spirit of the invention.

I claim:

1. A print roll comprising an iron body with an outer cylindrical surface having formed therein a plurality of spaced perforations, a separate metallic plug fitting each of said perforations with the outer surface of each plug flush with said cylindrical surface of said body, and a relatively thick electro-deposited copper layer on said cylinder having a continuously uniform outer surface, said copper layer being electrolytically united with said plugs.

2. A print roll comprising an iron body with an outer cylindrical surface having formed therein a plurality of spaced cylindrical perforations arranged radially of said body, metallic cylindrical plugs fitting said perforations with their outer surfaces flush with said cylindrical surface of said body, and a relatively thick electro-deposited copper layer on said cylinder having a continuously uniform outer surface, said copper layer being electrolytically united with said plugs.
